UNITED STATES PATENT OFFICE.

BLOOMFIELD BROWER, OF NEW YORK, N. Y.

DESIGN FOR A BASE FOR INKSTANDS.

Specification forming part of Design No. 7,597, dated July 28, 1874; application filed July 13, 1874.
[Term of Patent 3½ years.]

To all whom it may concern:

Be it known that I, BLOOMFIELD BROWER, of city, county, and State of New York, have invented a Design for a Base for Inkstands, of which the following is a specification:

The nature of my design is fully represented in the accompanying photographic illustration, to which reference is made.

A represents the base; B B, projecting standards, which may be of any selected shape; C C, inkstands, which are not new and not claimed by me.

The distinctive feature of my invention is the form or design of the base A and the lines and ornamentation on same, which are shown more fully in the illustration than I can describe them.

What I claim as my invention is—

The design for a base for an inkstand formed in the shape shown, and provided with the standards B, the whole being ornamented as illustrated.

BLOOMFIELD BROWER.
